OSCILLATOR-LIMITER-DETECTOR APPARATUS
AND METHOD

Walter D. Knight, Berkeley, Calif., assignor, by mesne assignments, to the United States of America as represented by the Secretary of the Navy

Filed Dec. 5, 1961, Ser. No. 157,285

2 Claims. (Cl. 329—150)

This invention relates to oscillator-limiter-detector apparatus and a method of operating the same. More particularly, it relates to what may be briefly termed a high-level oscillator especially adapted for use in studies of nuclear resonance.

Although the marginal oscillator-detector has been widely used because of its good sensitivity and relative simplicity, it suffers from several limitations which prevent its use for some problems in nuclear resonance. In particular, it is well known that the cathode-coupled circuit, as it was originally described in the article by R. V. Pound and W. D. Knight, "Review of Scientific Instruments," volume 21, page 219 (1950), permits of sensitive operation with good signal-to-noise ratio only in the range of RF levels between 0.01 and 1 volt. Schemes have been contrived which extend the range to microvolt levels, using the technique of increasing the gain of the RF amplifier. It has been shown that reliable operation can be achieved at low levels by incorporating a limiter in the feedback network. This, along with suitably high RF amplification, facilitates stable operation at low voltage levels.

An object of the present invention is to provide a modification of the cathode-coupled circuit which possesses some of the advantages of both the marginal and the limited modes of operation, and to provide a method for operating such a circuit.

Other objects and many of the attendant advantages of this invention will be readily appreciated as the same becomes better understood by reference to the following detailed description when considered in connection with the accompanying drawing wherein the single figure is a circuit diagram illustrating a preferred embodiment of the circuit of this invention.

The illustrated preferred embodiment of the circuit of this invention comprises a pair of multielectrode electron tube sections. These can be separate vacuum tubes but preferably form sections of a multi-unit tube, shown as a twin triode but conceivably a triode-pentode or other combination. By way of example the figure shows a 6BQ7A and the values of the circuit parameters are appropriate for this tube. The first half 2 of the tube is a cathode follower to which is connected the tank circuit including coil L and condenser C. The second half 4 of the tube operates both as a cathode-driven detector (which provides a small degree of automatic level control), and as a plate-limited RF amplifier. Regeneration is provided by the capacitor 6.

The amplifier plate circuit is returned to a variable direct voltage source, illustrated as a potentiometer 8. This plate supply voltage source is constructed so as to supply a plate voltage to the amplifier, between plate and cathode, which never exceeds about one half of the normal operating plate voltage for which the particular tube is designed. The desired limiting action of the apparatus is achieved by imposing this low plate voltage. The signal developed across the cathode resistor 10 of the first section of the triode is cathode-coupled to the section 4 of the triode through capacitor 12. The signal appearing at the cathode 14 is amplified and limited at the plate 16 and fed back to the input grid 18 via capacitor 6.

2

The plate load 20 for tube section 4 is shown as an RF choke, typically 1 millihenry, which is preferable, although a resistance could be substituted for it of say 1 to 10 kilo-ohms. It is across this load 20 that there is developed the regenerative voltage fed back through impedance 6 to grid 18. Impedance 6 should be at least as high and preferably higher than the LC impedance.

The cathode load 22 for tube section 4 is shown as an RF choke, typically 1 millihenry, but could be a resistance although this would not work as well.

At junction 24 appears, for example, +50 volts D.C., while at junction 26 appears ground which is 0 volts D.C. Hence 6 must be a D.C. blocking device such as a condenser as shown of small capacitance or a resistor plus a blocking condenser.

The network including resistor 28 and capacitor 30 is the detector filter. The network including resistor 32 and capacitor 34 forms an RF filter to keep RF voltage out of the output appearing at 36, which typically may be an audio voltage superimposed on the rectified RF voltage.

The 33-ohm resistors shown in the plate circuit and grid circuit of tube section 2 are parasitic suppressors.

Operation

25 The operation of the apparatus in its especially useful function in nuclear magnetic resonance studies is as follows. The coil L of the tank circuit surrounds a sample of material whose nuclear magnetic resonance is to be studied. The oscillation of the device starts by perhaps random noise. A D.C. voltmeter or like instrument is placed to measure the output, namely the voltage between output 36 and ground. The potentiometer 8 is adjusted until the desired RF voltage, for example 5 to 10 volts, appears across L as shown by a vacuum tube voltmeter across L. The vacuum tube voltmeter is used to calibrate the instrument connected between 36 and ground to serve as a D.C. voltmeter and thereafter the vacuum tube voltmeter is removed from the circuit.

30 Usually the sample of material to be examined is immersed in a magnetic field, which field is varied at an audio rate. As the magnetic field is varied and a point is reached at which the sample exhibits nuclear magnetic resonance, the Q of L diminishes because of absorption of energy by the sample. As the Q goes down, the voltage across L goes down and hence the output at 36 decreases in proportion. It may be noted that when the magnetic field surrounding the sample is varied continuously at an audio rate, there appears at the output terminal 36 an audio output superimposed on the direct voltage at 36. This output is what is measured in conducting the nuclear magnetic resonance studies and can be amplified with a tuned amplifier to reduce noise if desired.

35 This circuit is particularly suitable for application to problems in nuclear resonance which require RF levels between 1 and 20 volts R.M.S. Near one volt the operation is marginal; at higher levels the limiting action is predominant. The arrangement shown in the drawing has been used between 1 and 10 mc. and at levels between 40 1 and 10 volts R.M.S., with sensitivity equal to the best attainable with the usual marginal circuit.

45 Since there are no time constants in the audio-frequency range, very low modulation frequencies can be used, and motorboating does not occur. Additionally, it may be noted that this circuit easily works to frequencies of 50 mc. or above, since a separate RF amplifier is not required, and since the feedback network is simple.

50 The method of the invention comprises operating the circuit of the invention by supplying a plate supply voltage to the amplifier tube section of such a magnitude that the plate voltage, that is, the electrode voltage constituting

the potential difference between the plate and the cathode, is always maintained at less than one half of the normal operating plate voltage for the particular tube being used.

Obviously many modifications and variations of the present invention are possible in the light of the above teachings. It is therefore to be understood that within the scope of the appended claims the invention may be practiced otherwise than as specifically described.

What is claimed is:

1. An oscillator-limiter-detector comprising a first electron tube section serving as a cathode follower; a tank circuit connected between ground and the grid of said cathode follower to provide the input to said cathode follower; a second electron tube section operating as a cathode-driven detector, in which detection takes place between its grid and its cathode, and as a plate-limited RF amplifier; means cathode-coupling the signal from the output of the cathode follower to the cathode of said second tube section; means supplying a variable direct plate supply voltage to the plate circuit of said amplifier of such a magnitude that the plate voltage of said am-

plifier remains always at less than one half the normal operating voltage for said amplifier tube section; means connected between said input tank circuit and the plate of said amplifier tube section to feed back RF signal from said plate to said input tank circuit; and means connected between ground and grid in said amplifier tube section to provide a filtered, detected output essentially free of RF content.

2. The apparatus of claim 1 wherein said two tube sections constitute sections of a multi-unit tube.
